TELEPHONE NUMBER CHART

John D. Karle, 320 Chestnut St.,
Roselle Park, N.J. 07204

Filed May 28, 1969, Ser. No. 17,399

Term of patent 14 years

Int. Cl. D19—02

U.S. Cl. D74—1

Fig. 1

Fig. 2

FIG. 1 is a perspective view of the telephone number chart of my design, the both faces of which are identical except that one face has the first thirteen letters of the alphabet and the other face has the remaining thirteen letters of the alphabet; and

FIG. 2 is a fragmenary perspective view of a portion of the chart shown in FIG. 1 with the elastic reference member retracted in preparation for movement to a selected telephone number on the chart.

My design comprises a peripherally notched circular disc having heavy radial lines extending from a solid center portion dividing the disc into segments each denoted by a letter of the alphabet, with a plurality of light radial lines subdividing each segment, and in which said peripherical notches are each slightly offset clockwise beyond a respective one of said heavy or light radial lines.

I claim:

The ornamental design for a telephone number chart, substantially as shown and described.
